His Attorney.

UNITED STATES PATENT OFFICE

CHARLES L. HEISLER, OF SCHENECTADY, NEW YORK, ASSIGNOR TO GENERAL ELECTRIC COMPANY, A CORPORATION OF NEW YORK

APPARATUS FOR REPRODUCING SOUND FROM FILM RECORDS

Application filed March 29, 1929. Serial No. 351,066.

My invention relates to apparatus for reproducing sound from film sound records and particularly to the apparatus by which the record film is supported and moved at the point at which the record is read off the film. The object of my invention is the provision of improved apparatus of this character having advantages as to simplicity in construction and to convenience and efficiency of operation which will appear as the description proceeds.

My invention will be better understood from the following description taken in connection with the accompanying drawing, and its scope will be pointed out in the appended claims.

Referring to the drawing, Fig. 1 is a side elevation partly in section of a preferred embodiment of my invention; Fig. 2 is a view at right angles to that of Fig. 1 also partly in section; Fig. 3 is a cross sectional view of the photo-electric cell and its enclosing housing drawn to a greatly enlarged scale; Fig. 4 shows the photo-electric cell housing and socket member therefor separated from each other; and Fig. 5 is a side view of the photo-electric cell and its housing drawn to an enlarged scale.

In illustrating my invention I have chosen for the sake of greater simplicity to show it as a sound reproducer only, it being noted that the film is shown having a sound record thereon but no picture record. My invention is equally applicable, however, to a machine for projecting pictures and reproducing sounds from a film bearing both picture and sound records.

In the simplified form of my invention the enclosing casing 1 supports the reel housing 2 containing the take-off reel 3 and the take-up reel 4 whose construction is like that commonly employed in motion picture machines.

The film 5 is shown as being of the motion picture type having two marginal rows of sprocket tooth openings and as having a single sound record thereon adjacent one row of sprocket holes. The film is driven jointly by the sprocket 7 and the drum 8, these two members being connected by mechanism, now to be described, to the common motor-driven

shaft 9. Worm 11 on shaft 9 meshes with the worm wheel 12 which through gears 13, 14 and 15 drive shaft 16 of sprocket 7. Worm gear 12 also drives shaft 18 to which is secured at one end the flywheel 19 and at the other end the drum 8 but at a speed which is variable within certain limits and automatically controlled so that regardless of the amount of shrinkage the film may have undergone the drum will move the film at exactly the same speed as it is moved by the sprocket. The compensator for effecting this variable speed drive is driven from the worm gear 12 through an elastic or cushioning connection comprising the ring 20 of leather or other suitable material having a series of holes into which extend pins 21. Alternate pins are fixed in the worm gear 12 and the internal gear member 22 which is journaled on a sleeve of the worm gear. Loosely mounted on shaft 18 is the brake wheel 24 having the hub 25 which is eccentric with the shaft 18. Journaled in this eccentric hub is the gear member 26 having two sets of teeth forming two gears of which the pitch diameter of the one is slightly smaller than that of the other. The internal gear member 22 meshes with the larger gear and internal gear member 27 meshes with the smaller gear. This gear member 27 has a sleeve portion which is keyed to shaft 18 and which forms a bearing for the worm gear. Brake 28 is arranged to be applied with variable pressure to the brake wheel 24. The parts above described are so constructed that when the brake is not applied to the brake wheel and the gear mechanism associated therewith rotates freely the drum 8 is driven at such a speed that it moves the film appreciably faster than does the sprocket 7 regardless of how little shrinkage that the film may have undergone. If the brake is applied hard enough to hold the brake wheel immovable then the speed of the drum is decreased to such an extent that it moves the film appreciably slower than does the sprocket even though the film has undergone the maximum amount of shrinkage.

Between the sprocket and the drum the film passes through the two loops 30 and 31 engaged respectively by idlers 32 and 33 on 100

levers 34 and 35. The opposite ends of these levers are connected together by means of an adjustable spring 36, whereby the film tension in the two loops is approximately the same. 5 On the shaft 38 of lever 34 is the arm 39 having roller 40 which bears against brake lever 41. This lever is pivoted at 42 and is biased to the brake-applied position by the spring 43. As so arranged spring 43 opposes spring 36. In normal operation and after the first few feet of film has passed through the apparatus the brake 28 is but lightly applied to the brake wheel and there is no perceptible movement of the lever 34. Although the 10 reaction of the arm 39 on lever 34 is slight I compensate for this effect on the film tensions in loops 30 and 31 by slightly changing the lengths of the corresponding lever arms of levers 34 and 35, for example, by slightly 15 lengthening the lower or short arm of lever 35. Thus the film tension in the two loops 30 and 31 can be maintained during the operation of the machine very closely if not exactly the same. This condition I have found to 20 be essential if no slippage is to occur between the film and the drum.

For pressing the film against the sprocket 7 I have shown the two pressure rolls 46 and 47 and for pressing the film against the face 25 of the drum I have shown the two pressure rolls 48 and 49. Roll 48 also is a guide roll having flanges which position the film axially on the drum. The film it will be seen makes contact with the drum at two separated portions of its circumference, one of which is of greater extent than the other. Between these two contact portions the film leaves the drum and passes over the member 50 forming a skid and containing the photo-electric cell 30 51. Member 50 is shown formed in two parts, a metallic base or socket member 53 and a metallic cell housing 54. The socket member 53 is shown attached to a wall of the metal casting 1 and contains the socket contacts 55 with 35 which detachable connection is made to the contact plugs on the base of the cell 51. Preferably the cell is mounted in the housing 54, suitable packing such as, for example, felt being provided between the cell and the housing 40 walls. The housing with the cell is detachably secured in the socket 53 by any suitable means such, for example, as the clamp 56. I construct the housing 54 preferably of steel 45 thereby better to resist the wear of the film 50 and polish those portions of the cylindrical surface thereof which engage and guide the marginal portions of the film. Between the guide portions is the depressed portion 58. An optical system shown in part at 60 projecting through the casing wall focuses a beam of light down to a narrow band on the film as it passes over the skid. At a point directly beneath this focused light band the skid or housing 54 is provided with the light aperture 61 through which the light under the con-

trol of the sound record on the film may pass into the photo-electric cell, see Figs. 3 and 5. By depressing that portion of the housing beneath the part of the film bearing the sound record and in the case of a sound-picture film 70 the part of the film bearing both the sound and the picture record the film is subjected to less wear and the records are less liable to become scratched. Dust and dirt carried along by the film also is less liable to be carried into 75 the light aperture. To further insure against the collection of dust and dirt in the light aperture I make the additional depression 62 in the housing connecting with the aperture. Thus any particles of foreign matter such as 80 dust, dirt wax, etc., carried by the film toward the aperture will be swept away before finding lodgment in the aperture. If desired the cell housing may be provided with more than one light aperture as shown for example at Fig. 4 whereby in the event that the guide 85 portions of the housing become worn adjacent one aperture the housing may be turned relative to the socket and the cell to bring another aperture into use.

The drum 8 having the flywheel mounted directly on its shaft drives the film over the skid with a uniform speed independent of sprocket tooth, gear or other vibrations. The film engages the drum for the full width 90 of the film and, by reason of the fact that the film makes contact with the drum for a greater angle after it leaves the skid than before reaching it, that free stretch of film between the skid and the point of contact of 95 drum and roller 48 will always keep taut.

In the present illustration I have shown the leads 64 from the socket contacts 55 carried through a metallic conduit 65 to a metallic transformer housing 66. Within this 100 housing the leads connect with a suitable transformer, not shown, from which connections are made to amplifying apparatus of well known character and thence to a loud speaker or other translating device as desired.

What I claim as new and desire to secure by Letters Patent of the United States is:

1. Apparatus for supporting and moving at a uniform speed a sound record film comprising a drum having an inertia member associated therewith, means for rotating the drum, means for pressing the film against the face of the drum at two spaced peripheral portions thereof, a curved skid arranged to support a loop in the film between the points of contact of the film and the drum, a photo-electric cell and means for directing a light beam into the cell and through the film adjacent its point of support by the skid.

2. Apparatus for supporting and driving at a uniform speed a sound record film comprising a drum, an inertia member associated therewith, means arranged to cause the record film to engage the face of the drum at two spaced portions of its circumference, a

5 curved skid having a light aperture therein arranged to engage and support a loop in the film between said spaced portions, a photo-electric cell and means for projecting light through the aperture in the skid and the film thereon into the cell.

10 3. Apparatus of the character described comprising a photo-electric cell, a housing therefor having a light aperture and a smooth face over which a sound record film is adapted to be drawn, means for projecting a narrow light beam through the film and the aperture into the cell and means for drawing the film over said housing with a uniform speed in-
15 dependent of sprocket tooth vibrations comprising a drum, a flywheel directly connected therewith and means for causing the film to engage the drum both before and after it passes over said housing.

20 4. Apparatus of the character described comprising an enclosing casing, a photo-electric cell therein, a fixed housing for the cell detachably secured to the casing said housing having a light aperture therein and having portions at opposite sides of the aperture arranged to form continuous guide surfaces for a sound record film and means for moving the film at a uniform speed over said guide surfaces.

25 30 5. Apparatus of the character described comprising an enclosing casing, a contact socket member secured thereto, a film supporting housing member detachably connected to said socket member, a photo-elec-
35 tric cell mounted in said member and having contacts adapted to engage the contacts therein, said member having spaced portions forming continuous guide surfaces adapted to be engaged by the marginal portions of a
40 sound record film and having a light aperture therein arranged between said guide surfaces.

45 6. Apparatus of the character described comprising a photo-electric cell, a fixed mem-
50 ber enclosing the cell and forming a film sup-
port, said member having continuous curved guide portions adapted to be engaged by the marginal portions of a sound record film and having an intermediate depressed portion,
55 said member having a light aperture therein arranged between the guide portions thereof.

60 7. Apparatus of the character described comprising a photo-electric cell, a cylindrical housing enclosing the cell and forming a film support, said housing having portions forming continuous guide surfaces adapted to be engaged by the marginal portions of a sound record film and having an intermediate depressed portion, said housing having a light aperture therein in the depressed portion and having a further depressed portion connecting with the aperture at the trailing side thereof.

65 8. Apparatus of the character described comprising an enclosing casing, a shaft ex-

tending through a wall thereof, a drum in said casing secured to the end of said shaft, said drum being adapted to engage a film at two separate portions of its periphery, a housing detachably secured to said wall adjacent 70 said drum and adapted to form a support for a loop of said film between the contact portions of the film and the drum, and a photo-electric cell mounted in said detachable housing.

In witness whereof, I have hereunto set my hand this 28th day of March, 1929.
